UNITED STATES PATENT OFFICE

94,331

DESIGN FOR A SHOE

Charles H. Caldwell, Brockton, Mass., assignor
to Geo. E. Keith Company, Campello, Mass., a
corporation of Massachusetts

Application November 6, 1934, Serial No. 53,908

Term of patent 3½ years

To all whom it may concern:

Be it known that I, Charles H. Caldwell, a citizen of the United States, residing at Brockton, in the county of Plymouth and State of Massachusetts, have invented a new, original and ornamental Design for a Shoe, of which the following is a specification, reference being had to the accompanying drawing, forming part thereof.

In the drawing:

Figure 1 is a top plan of a shoe showing my new design; and

Figure 2 is a side elevation of the same. Both

sides of the shoe present substantially the same appearance.

The essential feature of the invention resides in the ornamentation of the material of which the shoe is made. As the design is applicable to shoes of various shapes and styles the representation of shoe is merely conventional, for showing an application of the design.

I claim:

The ornamental design for a shoe, as shown and described.

CHARLES H. CALDWELL.
